DESIGN FOR A WHISTLING TEAKETTLE OR SIMILAR ARTICLE

Clarence S. Keating, Evanston, Ill., assignor to
Kewaskum Aluminum Co., a corporation of
Wisconsin

Application March 8, 1935, Serial No. 55,781

Term of patent 7 years

To all whom it may concern:

Be it known that I, Clarence S. Keating, a citizen of the United States of America and resident of Evanston, county of Cook, and State of Illinois, have invented a new, original, and ornamental Design for a Whistling Teakettle or Similar Article, of which the following is a specification, reference being had to the accompanying drawing, forming a part thereof, wherein

Fig. 1 is a perspective view of a whistling teakettle showing my design; and

Fig. 2 is a side elevational view of the same.

I claim:—

The ornamental design for a whistling teakettle or similar article, as shown.

CLARENCE S. KEATING.
